UNITED STATES PATENT OFFICE.

O. G. AULD AND J. S. WHITING, OF STOCKTON, CALIFORNIA.

RIFFLE FOR GOLD-WASHING.

Specification of Letters Patent No. 14,847, dated May 13, 1856.

To all whom it may concern:

Be it known that we, OSSIAN G. AULD and JASPER S. WHITING, of Stockton, in the county of San Joaquin and State of California, have invented a new and Improved Riffle for Saving Fine Gold; and we do hereby declare that the following is a full and exact description thereof, reference being had to the accompanying drawings.

The nature of our invention consists in making the openings in our riffle of such a shape, that in gold washing with a current of water, an eddy is created, whereby if quicksilver is used, all the gold is brought in contact therewith, while even if no quicksilver is used, all tendency to escape is overcome by the action of said eddy and the shape of the flanges.

The "eddy riffle" is a flat oblong or square piece of wood and iron, or simply of iron, made to fit into ordinary mining "sluices"—the dimensions to vary according to the width of said "sluices," and the thickness of the bottom board of same. When made of iron the upper surface is perforated with circular holes, of from a half an inch to an inch in diameter, and extending one quarter way through the thickness of the metal, until they meet corresponding circular holes entering from the

lower side, with a diameter from two to three times as great—thus forming cylindrical spaces on the lower side, with a height of three quarters the thickness of the metal and terminated above by flanges surrounding the openings or holes mentioned before.

When made of wood and metal, the wood is first perforated with circular holes of any suitable size and then covered with sheet or cast iron or any other metal, also perforated with circular holes of a less diameter, so placed as to come above the former, and form similar cylindrical spaces to those above referred to. Sectional views of these spaces will be seen in the accompanying drawings.

What we claim as new, in riffle boxes, and for which we desire to secure Letters Patent is—

The use of circular cavities or receptacles, constructed in the manner herein shown, having the neck of one diameter and the lower portion of an enlarged diameter, so as to operate in the manner specified.

OSSIAN G. AULD.
JASPER S. WHITING.
